UNITED STATES PATENT OFFICE.

IVOR D. THOMAS, OF PALMYRA, OHIO, ASSIGNOR TO THE WELLMAN-SEAVIER-MORGAN COMPANY, OF CLEVELAND, OHIO, A CORPORATION OF OHIO.

DOOR-EXTRACTOR-OPERATING MECHANISM.

Application filed April 15, 1925. Serial No. 23,224.

This invention relates to operating mechanism for door extractors such as employed for removing and replacing the doors of coke ovens. Such door extractors are usually mounted upon a suitable carriage or car which runs on a track which extends along the front of a row of ovens so that the carriage may be positioned in front of any oven from which a door is to be extracted, the carriage being provided with a suitable door handling device such as a ram mounted for movement toward and from the oven. The door handling device is provided with suitable means for engaging and lifting the door and for pulling the door outwardly from out of its frame. In removing the door it is pulled outwardly to free it from its frame and in replacing the door it is moved into the frame and pushed into tight engagement therewith.

Since the doors are usually quite heavy and are sealed in their frames during the operation of the oven to prevent escape of gases considerable power is required to strip a door from its frame. When the extractor mechanism is hand operated it is necessary in order to enable sufficient power to be applied to strip the doors to provide power multiplying devices between the hand wheel and door engaging member which cause the movement of the engaging member to be very slow.

It is the object of the present invention to provide a hand operating mechanism by which the necessary power may be applied at such times as is necessary or desirable in the extraction or replacement of the doors and by which the door handling member may be moved rapidly after the door is freed from its frame to quickly shift the door clear of the oven structure, or, in replacing the doors, to move the door quickly into its frame.

The following description and accompanying drawings set forth in detail certain means embodying the invention, the disclosed means, however, constituting but one of the various mechanical forms in which the principle of the invention may be employed.

Reference should be had to the accompanying drawings forming a part of this specification in which Fig. 1 is a top plan view of the extractor; Fig. 2 is a side elevation thereof; Fig. 3 is a section on line 3—3

of Fig. 1 looking in the direction indicated by the arrows; Fig. 4 is a section on line 4—4 of Fig. 3 looking in the direction indicated by the arrows; Fig. 5 is an axial section through the hand wheel and planetary gearing.

In the accompanying drawings the superstructure of the carriage on which the door extractor is mounted is indicated by the numeral 1 and mounted in the superstructure 1 there is a reciprocable ram 2 supported upon rollers 3 and held in place thereon by guide rollers 4. The ram 2 is mounted for movement toward and from the door and carries suitable door engaging hooks not shown. The ram 2 has attached to the top thereof a rack 5 which is engaged by a pinion 6 carried by a shaft 7 extending transversely over the top of the ram and journaled in channel frame members 8 which extend along opposite sides of the ram. The pinion 6 is fixed to the shaft 7 and is driven through a large gear 9 also fixed to the shaft 7 which meshes with a small gear 10 fixed to a countershaft 11 journaled in the frame members 8 above and to one side of the shaft 7. An operator's cab 12 is mounted on the carriage at one side of the frame members 8 and the countershaft 11 extends through the wall of the cab 12 and is adapted to be operated by a hand wheel 13 mounted upon the inner end thereof within the cab. The hand wheel 13 is loosely mounted upon the inner end of the shaft 11 and is provided with a suitable handle 14 by which it may be turned. The hub 15 of the hand wheel has an outwardly projecting flange with a gear 16 formed thereon, the gear 16 meshing with a larger gear 17 rotatably mounted on a stub shaft 18 carried by an arm 19 which projects radially from the shaft 11 and has a collar 20 fixed to the shaft. A planetary gear casing 21 encloses the gears 16 and 17 and the gear supporting arm 19. The casing 21 is rotatably mounted with respect to the shaft 11 and has an inner side plate 22 which is rotatably mounted on the hub 15 of the hand wheel and an outer side plate 23 which is rotatably mounted on the collar 20 fixed to the shaft 11. The plate 23 has an inwardly extending flange 24 which is bolted to the inner plate 22 and upon the interior of the flange 24 there is formed an internal gear 25 which meshes with the gear 17 carried by

105 110

the arm 19. The casing 21 is provided adjacent the periphery with a sliding pin 26 which extends from one side to the other of the casing. The pin 26 is provided with an 5 outwardly projecting handle 27 which is movable in a slot 28 in the periphery of the casing. By means of the handle 27 the pin 26 may be projected to either side of the casing 21. When the pin 26 is projected 10 inwardly it extends into the hand wheel 13, lies in the path of a spoke of the hand wheel so that the casing 21 will be turned with the hand wheel. By shifting the pin 26 in the opposite direction, it may be projected 15 into an opening 29 formed in the wall of the cab 12 locking the casing 21 against rotation.

When the planetary gear casing 21 is locked to the hand wheel, the gear 17 meshing with the internal gear 25 and with the gear 16 on the hub of the hand wheel is locked against rotation causing the arm 19 and the shaft 11 to rotate with the hand wheel. When the planetary gear casing 21 25 is locked against rotation by engagement with the pin 26 in the opening 29, the gear 17 is rotated by the gear 16 when the hand wheel is turned and is caused to travel around in the casing on the internal gear 25 causing the shaft 11 to be rotated in the same direction as the hand wheel but at much slower rate of speed. When the ram 2 is being moved up to a door, the casing 21 will be locked to the hand wheel so that a 30 fairly rapid movement may be imparted to the ram. After the ram is engaged with the door, the casing 21 will be locked against rotation by a movement of the pin 26 in the opening 29 so that upon rotation of the hand wheel in a direction to strip the door, the rotation of the shaft 11 will be at a 35 much lower rate of speed than the rotation of the hand wheel 13, causing a corresponding increase in the power applied to the door 40 to strip it from its frame. As soon as the door has been loosened, the locking pin 26 may be shifted to lock the casing 21 to the hand wheel so that upon continued rotation of the hand wheel, the door may be rapidly 45 moved to a position clear of the oven structure. In replacing the door, the casing 21 will be locked to the hand wheel until the door has been moved into its frame whereupon the casing may be locked against rotation to decrease the rate of movement of the 50 ram and correspondingly increase the force applied to the door to push it into tight engagement with its frame.

Having described my invention, I claim—
60 1. In a device of the character described, a supporting frame, a shaft mounted on the frame, a hand wheel rotatably mounted on the shaft, a planetary gear casing rotatably

65 mounted upon the shaft alongside the hand wheel, said hand wheel having a hub projecting into the casing, a gear fixed to the hub within the casing, an internal gear fixed to said casing, an arm fixed to said shaft and extending within said casing, a gear carried by said arm and meshing with said internal gear and with the gear on the hub and means carried by said casing for locking the same to the hand wheel or to the frame.

2. In a device of the character described, 70 a supporting frame, a driving shaft rotatably mounted in the frame, a hand wheel rotatably mounted on said shaft, a planetary gearing interposed between the hand wheel and shaft and comprising a ring gear rotatable upon said shaft, a central gear and an intermediate gear meshing with the ring gear and central gear, the central gear and the intermediate gear being carried one by the shaft and one by the hand wheel, and a locking member carried by said ring gear by 75 which said ring gear may be locked to the hand wheel or to the frame.

3. In a device of the character described, 80 a supporting frame, a shiftable member mounted on the frame, means for operating said shiftable member comprising a shaft and means operated by the shaft for moving said member, a hand wheel rotatably mounted on the shaft, a member rotatably mounted on the shaft adjacent the hand wheel, an 85 internally toothed gear carried by said rotatable member, a gear fixed to the hand wheel, an arm fixed to said shaft, a gear carried by said arm and meshing with the internal gear and the gear fixed to the hand wheel, and a shiftable locking member carried by said rotatable member for locking said rotatable member to the handwheel and for locking the same to the frame against movement in either direction. 90

4. In a device of the character described, 95 a supporting frame, a ram mounted on the frame, means for operating said ram comprising a driving shaft and means operated by the shaft for moving said ram, a hand wheel rotatably mounted on the shaft, a planetary gear casing rotatably mounted upon the shaft alongside the handwheel, said hand wheel having a hub projecting into the casing and having a gear thereon within the 100 casing, an internal gear fixed to said casing, an arm fixed to the shaft and extending within said casing, a gear carried by said arm and meshing with said hub and internal gears, and a shiftable locking member carried by said casing and movable either into engagement with said handwheel or with the 105 supporting frame.

In testimony whereof, I hereunto affix my signature.

IVOR D. THOMAS.
